Primary Examiner — Karen E Kearney(74) *Attorney, Agent, or Firm* — James J. DeCarlo; Greenberg Traurig, LLP(57) **CLAIM**

The ornamental design for a portion of a display screen with graphical user interface, as shown and described.

DESCRIPTION

The FIGURE is a front view of a portion of a display screen with a graphical user interface, showing the new design. The broken line showing of the display screen portion is included for the purpose of illustrating environmental structure and forms no part of the claimed design.
